US00D941825S

(12) **United States Design Patent** (10) **Patent No.:** **US D941,825 S**
(45) **Date of Patent:** **** Jan. 25, 2022**

(54) **BEZEL INCLUDING A DISPLAY**

(71) Applicant: **WOWZA MEDIA SYSTEMS, LLC**,
Golden, CO (US)

(72) Inventor: **Ed Nelson Caggiani**, Loveland, CO
(US)

(73) Assignee: **WOWZA MEDIA SYSTEMS, LLC**,
Golden, CO (US)

(**) Term: **15 Years**

(21) Appl. No.: **29/673,940**

(22) Filed: **Dec. 18, 2018**

Related U.S. Application Data

(62) Division of application No. 29/607,464, filed on Jun.
13, 2017, now Pat. No. Des. 840,406.

(51) **LOC (13) Cl.** **14-02**
